(57) **CLAIM**

The ornamental design for milling machine measurement apparatus, as shown and described.

DESCRIPTION

FIG. 1 is a perspective view of my new design for a milling machine measurement apparatus.

FIG. 2 is a front elevational view of my new design for a milling machine measurement apparatus.

FIG. 3 is a right side elevational view of my new design for a milling machine measurement apparatus.

FIG. 4 is a back elevational view of my new design for a milling machine measurement apparatus.

FIG. 5 is a forward-facing top plan view of my new design for a milling machine measurement apparatus; and,

FIG. 6 is a backward-facing top plan view of my new design for a milling machine measurement apparatus.
